UNITED STATES PATENT OFFICE.

FRANK B. DOW, OF BIG SANDY, TEXAS.

GUIDE AND DEPTH-REGULATOR.

1,321,367.

Specification of Letters Patent. Patented Nov. 11, 1919.

Application filed September 15, 1919. Serial No. 323,913.

To all whom it may concern:

Be it known that I, FRANK B. Dow, a citizen of the United States, residing at Big Sandy, in the county of Upshur and State of Texas, have invented certain new and useful Improvements in Guide and Depth-Regulators, of which the following is a specification.

This invention relates to new and useful improvements in guides and depth regulators for shovel plows.

The object of my invention is to guide a shovel plow in the center of the furrow and regulate the depth to which the shovel enters the ground, and to provide simple and easy means of adjusting the parts involved.

In carrying out the invention a hanger is secured to the beam of the plow in rear of the standard in such a manner that suitable adjustment may be had. A support terminating in a shoe is adjustably connected with the hanger, the shoe regulating the depth of plowing. A guiding blade is secured in the shoe and is adjustable in such a manner as to take up the wear.

One of the features of the invention is to allow ample room between the shovel and the shoe to permit the heel bolt to be easily and quickly adjusted when it is desirable to remove or adjust the shovel.

The invention will be more readily understood from a reading of the following specification and by reference to the accompanying drawings, in which an example of the invention is shown, and wherein:

Figure 1 is a side elevation of a shovel plow equipped with a guide and depth regulator constructed in accordance with this invention,

Fig. 2 is a detail of the hanger and adjusting links,

Fig. 3 is a detail of the support and shoe with guiding blade, and

Fig. 4 is a sectional view of the shoe on line 2—2 of Fig. 3.

In the drawings the numeral 5 designates the beam of a shovel plow with a standard 6 carrying a suitable shovel 7. A U-shaped hanger 8 is clamped to the beam 5 by means of transverse bolts 9 and 10 passing through the upper and lower surfaces of the beam, the lower end of the hanger being reduced to receive and hold an angular support. An angular support 11 having a vertically disposed slot 12 adjacent its upper extremity and terminating in a bifurcated shoe 13 at its

lower end is received into the lower end of the hanger and clamped therein by means of transverse bolts 14 and 15 which pass through the hanger and the slot in the support, said slot providing for vertical adjustment of the support in the hanger.

Adjusting links 16 and 17 having their lower ends connected with the lower end of the hanger by means of the transverse bolt 14 and being offset to engage the standard 6 to which they are secured by means of a transverse bolt 18 are adjustable forward and backward by means of longitudinally disposed slots 19 and 20 in the links adjacent their upper ends which engages said bolt 18.

A guiding blade 21 is mounted in the shoe and pivotally held between the furcations of the latter by means of a transversely disposed bolt 22. The said guiding blade is frictionally held in place and is frictionally adjustable by tapping or striking same on its upper edge with a hammer to compensate the wear on same.

It will be noted that with this simple construction easy and quick adjustment can be had and by having ample clearance between the shovel and the shoe the heel bolt may be easily removed without necessitating the removal of the regulating device.

What I claim is:

1. In a guide and depth regulator for shovel plows, the combination with a shovel plow having a beam and a standard, a hanger clamped to the beam in rear of the standard, means for adjusting the hanger forward or backward in relation to the standard, an angular support terminating at its lower end in a bifurcated shoe, and means for vertically adjusting the support in relation to the hanger.

2. In a guide and depth regulator for shovel plows, in combination with a shovel plow having a beam and a standard, a hanger clamped to the beam in rear of the standard, means for adjusting the hanger forward or backward in relation to the standard, an angular support received and held in the lower end of the hanger, a bifurcated shoe adjacent the lower end of the support, and means for vertically adjusting the support in relation to the hanger.

3. In a guide and depth regulator for shovel plows, in combination with a shovel plow having a beam and a standard, a hanger clamped to the beam in rear of the standard, adjusting links connecting the

lower end of the hanger with the standard, longitudinally disposed slots in the links for adjusting the hanger backward or forward in relation to the standard, an angular support received and held in the lower end of the hanger, a vertically disposed slot in the support adjacent the upper end of the latter for vertically adjusting same in relation to the hanger, a bifurcated shoe adjacent the

lower end of the support, a guiding blade 10 frictionally held in the shoe between the furcations of the same, and means for frictionally adjusting the blade for compensating the wear on same by striking the back of the blade with a hammer. 15

In testimony whereof I affix my signature.

FRANK B. DOW.
